UNITED STATES PATENT OFFICE.

EDWARD FARWELL, OF WEYMOUTH, ENGLAND.

DRAWPLATE OF BAKING-OVENs.

1,369,641.

Specification of Letters Patent. Patented Feb. 22, 1921.

Application filed November 25, 1919. Serial No. 340,597.

To all whom it may concern:

Be it known that I, EDWARD FARWELL, a subject of the King of Great Britain and Ireland, and a resident of Weymouth, 5 county of Dorset, England, have invented a certain new and useful Improvement in Drawplates of Baking-Ovens, of which the following is a specification.

In present-day practice, and especially 10 in small bakeries, much inconvenience and trouble is experienced owing to the amount of room taken up by the drawplate of an oven when drawn out.

This invention relates to drawplates of 15 baking ovens, of the kind in which the baking surface or drawplate is flexible, that is to say, composed of a series of flat plates, strips or sections, articulated together, forming an endless web which can be rolled 20 in or out of the oven.

In a drawplate as above set forth, the web passed around polygonal or cylindrical drums or chain wheels, carried by shafts horizontally mounted in the ends of a 25 frame wagon or carriage which was provided with rollers adapted to run on rails located inside the oven, and when rolling out the drawplate it was necessary to partly pull out the frame wagon or carriage, and 30 with it the drawplate, before said drawplate could be wound along, by rotating the shaft of the front drums or chain wheels by means of a handle on the end of said shaft.

According to the present invention, the 35 frame wagon or carriage, and its rollers, is dispensed with, and each plate, strip or section of the drawplate is, at its ends, provided with side extensions which carry a roller adapted to run in grooves inside the 40 oven and disposed above and below the steam pipes, extending the length of the oven, said grooves being connected together by semi-circular grooves formed on the exterior of a semi-circular chamber 45 forming part of the front plate of the oven.

On a shaft which extends transversely and centrally through this chamber are located the front sprocket wheels, and in the rear end of the oven are mounted the rear 50 sprocket wheels, and the chains passing over said sprocket wheels are affixed to the underside of the central plate, strip or section of the drawplate, the arrangement being such that as the front shaft is rotated by 55 means of a handle or hand wheel affixed thereto, the drawplate is caused to travel

outward and then inward to underneath the steam pipes in the oven, or vice versa as the case may be.

As a modification, the rollers on the side 60 extensions of the plates, strips or sections may be dispensed with, and said side extensions be arranged to take in and travel in the before mentioned grooves.

For a clear understanding of the present 65 invention reference is to be had to the following description and accompanying sheet of drawings, wherein:—

Figure 1 is a longitudinal sectional view illustrating an embodiment of the invention. 70

Fig. 2 is an end front view, partly broken away.

Fig. 3 is a vertical transverse sectional view taken on line x, y of Fig. 1.

Fig. 4 is a vertical fragmentary sectional 75 view hereinafter referred to.

Fig. 5 is a modification, also hereinafter referred to.

Like letters of reference indicate corresponding parts in the several figures. 80

In carrying out the invention, the drawplate is constituted by a series of flat plates or sections a , provided with side extensions a' —Figs. 1, 3 and 4—and flexibly connected together in any suitable manner. This 85 plate is, by means of rollers a^2 , located at the sides of said plate, adapted to work in upper and lower guides b, b' respectively, mounted in or carried by the side walls b^2, b^3 of the oven b^4 , and said drawplate is 90 connected in any suitable manner at a^3 to two endless chains c, c' passing around pairs of front and rear sprocket wheels c^2, c^3 , mounted on rotatable shafts c^4, c^5 respectively. 95

The front sprocket wheels c^2 are housed within a chamber or hood carried by the frame d' in which the oven door d^2 slides with the aid of racks and pinions d^3, d^4 in the known manner. 100

The chamber d , which at its front end is semi-circular, is provided respectively with semi-circular end grooves d^5, d^6 thereon, said grooves d^5, d^6 forming the continuation of the upper and lower grooves b, b' . 105

On rotating the shaft c^4 of the front sprocket wheels c^2 by means of a hand wheel c^6 thereon, or by a suitable arrangement of mechanism, the drawplate is caused to travel forward, the oven door being raised, through 110 the opening b^5 in the front wall and door frame, and gradually returned into the oven.

through an opening b^6 in the lower part of the frame d^1 and front wall to a position beneath the steam pipes e of said oven, the rollers a^2 of the drawplate traveling along 5 the grooves b , around the semi-circular grooves d^5 , d^6 and grooves b^1 as in Fig. 4, the sections of the plate taking, lengthwise, between the grooves d^5 , d^6 on the chamber d .

Reverse rotation of the hand wheel c^6 or 10 actuating mechanism, returns the drawplate to its position in the oven and above the steam pipes e , it being charged during such return, the opening b^6 in the lower part of the oven being closed, in a steam-tight manner, as the end of the drawplate leaves the oven, by means of a slidable or other door f , the upper opening b^5 being closed by the door d^2 as the end of the drawplate passes 15 into the oven.

20 Instead of employing rollers to take in the grooves b , b' , d^5 , d^6 , the drawplate may—as shown in Fig. 5—by its side extensions a^1 , take, in a slidable manner, directly in said grooves, the semi-circular grooves d^5 , d^6 being modified to allow of said side extensions 25 turning in said semi-circular grooves d^5 , d^6 .

I claim:

1. A drawplate structure for baking ovens including in combination with the oven having an opening, of a pair of parallel guides arranged within the oven, a hood arranged at one end of the guides and having therein a substantially U-shaped guide for connecting the said first mentioned guides, a drawplate 30 slidably mounted in the guides, sprockets located within the hood, sprockets at the opposite end of said guides, a chain working over said sprockets in the hood and at the opposite ends of the guides and connected 35 with said drawplate, and means for operating the sprockets in the hood.

2. A drawplate structure for baking ovens including in combination with the oven having an opening, of upper and lower sets of 40 parallel guides arranged within the oven and extending to the said opening, a hood including substantial U-shaped guide tracks 45 for connecting with the upper and lower guides of the said sets to form continuous guides at one end of the oven, a shaft in said 50 guides, sprockets on said shaft, a shaft and

sprockets at the end of the upper and lower guide sets opposite the opening in the oven, chains engaging said sprockets, a drawplate having a slidable engagement with the upper and lower sets of guide rails and engaging 55 said chains, an operating wheel carried by the shaft in said hood, and doors located at each side of the opening in the oven and adapted to slide toward the ends of the hood 60 to close the opening.

3. A drawplate structure for baking ovens including in combination with the oven having an opening, a flexible drawplate mounted within the oven, means including a hood 65 at the opening of the oven for permitting the shifting of the flexible drawplate from one position to another, and doors located at opposite sides of the opening and slidable toward the hood to close the oven opening.

4. A drawplate structure for baking ovens including in combination with the oven having an opening, upper and lower sets of guide rails within the oven, a flexible drawplate 70 slidable in the guide rails, means located at the opening of the oven for connecting the upper and lower sets of guide rails to permit of the transfer of the drawplate from the upper guide rails to the lower guide rails, and doors slidable in opposite directions and coöperating with the edges of the 75 hood to close the opening.

5. A drawplate structure for baking ovens including in combination with the oven having an opening, of guide rails engaged with 80 in the oven, a flexible drawplate slideable in the guide rails, a frame fitted to the oven at the opening and carrying therewith a hood, said hood having means for connecting the upper and lower set of guide rails to form 85 a continuous channel for the drawplate whereby it may move from the upper set of guide rails to the lower set and vice versa, means for shifting the drawplate, and doors 90 also carried by said frame and coöperating with the edges of the hood to completely close the opening of the oven when desired.

In testimony whereof I have affixed my signature hereto this 8th day of October, 1919.

EDWARD FARWELL.
